A. C. DAY

TOY AND ELEMENTS FOR CONSTRUCTING IT

Filed Jan. 17, 1923

Alfred Carlyle Day,
by Frank S. Ahlemann
Atty.

UNITED STATES PATENT OFFICE.

ALFRED CARLYLE DAY, OF MELBOURNE, VICTORIA, AUSTRALIA.

TOY AND ELEMENTS FOR CONSTRUCTING IT.

Application filed January 17, 1923. Serial No. 613,264.

To all whom it may concern:

Be it known that I, ALFRED CARLYLE DAY, a subject of the King of Great Britain and Ireland, residing at 8 Wright's Lane, Mel- 5 bourne, in the State of Victoria, Common- wealth of Australia, have invented certain new and useful Improvements in Toys and Elements for Constructing Them; and I do hereby declare the following to be a full, 10 clear, and exact description of the invention, such as will enable others skilled in the art to which it appertains to make and use the same.

This invention relates to toys and elements 15 thereof, its object being to provide simple elements which allow of building up and dissembling interesting toys of many forms, with or without working parts. With these elements manufactured and natural objects 20 can be imitated.

While the principle of the invention can be associated with different types of mechanical elements such as rods, bars, plates and the like, the accompanying drawing to- 25 gether with the specification will, it is thought, suffice for one skilled in the art to gain a knowledge of the importance and advantages of the invention and the preferred forms in which it may be embodied. 30 Each element is of any suitable cross section, and dimensions and some of the elements are thickened or weighted at desired parts; but thickening or weighting introduces no novelty.

Besides having bodies of old form my 35 elements have novel means to facilitate the connecting and fastening of the elements in desired relative positions. These means include tongues and apertures, distance pieces, 40 and connecting and locking elements, as de- scribed hereinafter.

The drawings herewith show perspective 45 views.

Figure 1 shows a strip element, each end having an apertured tongue.

Figure 2 shows part of a strip having a simpler tongue.

Figure 3 shows part of a channelled strip.

Figure 4 shows a strip having each end 50 set at an angle to the body.

Figure 5 shows a distance piece.

Figure 6 shows a locking element.

Figure 7 shows a locking bar.

Figure 8 shows a connecting element.

Figure 9 shows a simpler connecting ele- 55 ment.

Figure 10 shows a modification of Figure 9.

Figure 11 shows part of a constructional element of block form. 60

Figure 12 shows parts of five strip ele- ments locked together.

Figure 13 shows strips, a shaft, and a wheel, connected together.

Figure 14 shows a locking member which 65 is U shaped and perforated.

Figure 15 shows a wedge for use with the member of Figure 14.

Although I show in Figures 12 and 13 simple combinations, elaborate combinations 70 can be produced. Individually the parts shown in Figures 5, 7, and 15 are not new, nor is it new to have, for connecting pur- poses, circular holes in toy elements.

In the drawings, 1 indicates elements of strip form, 2 (Figure 3) is a channelled ele- 75 ment; 3 (Figure 11) is a block element. 5, 6, and 7 (Figures 8 to 10) are connecting elements; 8 and 9 (Figures 6, 7 and 15) are wedges, 9^a (Figure 5) is a spacing piece, or 80 washer shown circular, any suitable form being usable; and 9^b (Figure 14) is a per- forated locking member called herein for brevity a clip. Element 7 has aligning flanges 7^a to act as shown in Figure 12. 85

The elements have narrow ends or project- 90 ing parts forming tongues 4, so that some tongues are in the same planes as the element bodies as in Figures 1 and 2, while others extend, as in Figures 4, and 8 to 10, 90 at an angle to the body.

As these tongues are at their base nar- 95 rower than the element bodies, shoulders 4^a are formed, their function being to act as abutments for parts of other elements with which the tongues engage.

After such engagement is effected a fixing means is inserted at the outer side of the added element. The simplest ap- 100 pertures I use, to allow of making connec- tions, are circular holes 12; or plain slots 11, and/or crossed slots 11^a. But my im- proved apertures are of simple form cen- trally, (shown by circular holes 10) but have diametral extensions, shown as pairs 105 of slots 10^a, any number of pairs of such slots being extended from a hole.

In some cases the element body, see Fig- 110 ures 8 to 10, and part of Figure 4, forms abutments at the tongue base. A tongue of another element is engageable with any pair of slots 10^a, and is likewise engageable

with a plain slot 11, and with each slot of crossed slots 11^a. The edge slotted holes have, however, functions not characterising plain or crossed slots. Thus holes 10 or 12 allow of rotation of any shaft engaging such hole, while the slots 10^a prevent parts engaging them from rotating.

The diameter of each hole 12, and the distance between the ends of a pair of slots 10^a, is equal in each case to the length of a slot 11. Tongues 4 fit slots 11, or 11^a, and pairs of slots 10^a, and when so fitted are held against rotation. But when in holes 12 the tongues can rotate.

Each tongue has a slot or hole to be used for locking the element engaged by the tongue in assembled position. In each tongue of Figures 2 to 4 and 9, 10^a there is a simple slot; in Figures 1 and 8 the tongue 15 has a hole having a pair of diametral slots.

In edges of my elements,—see the tongues in Figures 1 and 8—I provide at any suitable points oppositely located nicks 4^b each pair of nicks being engageable by a locking element, the use of which renders use of the tongue slot unnecessary.

Thus the locking element 8 has prongs 8^a. It also has tapering side flanges 8^b. The distance from abutments 4^a to nicks 4^b is predetermined to facilitate assembling elements and fixing them in desired positions. To avoid looseness when the connected elements and locking means do not fill the space available on a tongue, I add 30 one or more spacing or distance pieces 9^a.

A shaft 14 is shown built into a toy construction containing a strip 1, in Figure 13, and to prevent longitudinal motion of the shaft relatively to the strip, I attach 40 two clips 9^b to the shaft, one at each side of the strip. Each clip has a pair of apertures 9^c adapted to receive a key or wedge 9, which will hold the clip firmly. At 45 the shaft has a flat surface to enable a wedge 9 to enter a notch 15^a in the wheel

15, to fix the latter on the shaft so that neither can rotate independently. The strips 1 in Figure 13 are connected by an element 6, the tongue 4 of which passes through a hole in each strip, the tongue carrying a distance piece 9^a and a wedge 9 inserted in hole 11, the base of element 6 abutting against a strip.

From the explanations already supplied it will be noted how, in Figure 12, the parts 55 6, 7, 8, 9 and 9^a are utilized. Two strips 1 are held in line by a part 7. (See Figures 9, 10, 6, 7 and 5 respectively.)

In addition the part 8 in Figure 12 has its prongs engaging tongue nicks 4^b; and 60 at another part of Figure 12 two distance pieces 9^a are used to fill up the space available between a tongue 4 and a locking wedge 9.

I claim:—

1. A toy element of strip form having a tongue of reduced width, a second element having an aperture to receive the said tongue, the said tongue having shoulders to abut the second element, the said tongue having nicks in its edges; and a locking member having limbs adapted to enter the said nicks.

2. The construction in claim 1, but the relation of parts being such that there is 75 a space between the nicks and the tongue base to receive a distance piece in addition to the second element.

3. A toy element connecting element having a base, a tongue formed by an apertured part of reduced width extending at an angle to the base, the said aperture being adapted to receive part of another element, and opposed nicks in the tongue to receive a locking member.

In witness whereof I have hereunto set my hand.

ALFRED CARLYLE DAY.

Witness:

G. G. TURRI.
